UNITED STATES PATENT OFFICE

2,579,889

ADVERTISING DISPLAY DEVICE

Alvin Weinberg, University City, Mo.

Application June 12, 1946, Serial No. 676,138

2 Claims. (Cl. 40—126)

1

This invention relates to improvements in advertising display devices.

An object of the invention is to provide a display device which comprises a replica of a commercial glass bottle container of very light weight, simulating a container for a particular product with the commercial labels attached, and which device may be attached to a display rack or shelf, without damage thereto, in a selected place to attract the attention of customers to the particular product.

Another object of the invention is to provide such a device formed of a light plastic material, with convenient means for attaching the same at selected display points, so that it will not interfere with or mar the store fixtures.

Additional advantages of the invention will be apparent from the following detailed description taken in connection with the accompanying drawing, in which:

Fig. 1 is a side elevation of the advertising device in simulation of a bottle, supported on supports attached to the side faces of a vertical wall of a store fixture;

Fig. 2 is a cross-sectional view taken substantially on the line 2—2 of Fig. 1, with a portion of the support members being shown in dotted lines; and

Fig. 3 is an enlarged sectional view taken substantially on the line 3—3 of Fig. 1.

It is known to store operators, such as liquor stores, drug stores, and certain other retail stores, that the best manner of attracting attention of customers is to place within the view of the major number of customers entering the store, a replica of the package in which a particular product is sold.

Particularly, with bottled products, which are usually displayed only in display fixtures such as racks or shelves, the large number of the bottles massed together do not attract particular customer attention. It is also known that in retail stores, there are certain places in the store, which are seen by the major number when making purchases, such, for example, as near a cash register, or central sales counter.

Likewise, the psychology of purchasers is to have their attention attracted not by display devices that are either elevated above or depressed below the normal eye level, but if the display is at eye level, there is a tendency to catch the attention of the observer.

Therefore, there is a real need for the display device comprising a replica of a commercial package which may be easily attached without

2

damage to the fixtures at selected places by the store operator, particularly where it is desired to feature a certain selected product.

It is necessary, in a well operated store, to avoid defacing the fixtures or displaying products so that they will interfere either with the customers or with the store operators.

It is to the satisfaction of these objectives that the structure of the present invention lends itself.

The improvement includes the provision of a replica of a bottle 1, which is preferably made of a very light plastic material so that it may be easily and conveniently supported by readily attachable supports, and which may be conveniently moved from display points in the store.

The contour of the bottle, as well as the commercial dress thereof, is an exact simulation of the usual glass commercial package so that, when viewed from the front, it will impress an observer as being a complete commercial package.

The body of the bottle has a cutout portion 2 in its rear wall, the cutout portion being limited in width so that it will not be observed from any of the ordinary angles in front of the device at which it would be viewed by customers in the store.

The cutout portion provides for the internal attachment of a support which, as illustrated, comprises an integral web 3 formed at each of the sides of the interior of the body portion, said web being preferably formed integral or securely attached to the interior wall of the body of the bottle, as best illustrated in Fig. 2.

At the forward end of each web, a flexible strap 4 is pivotally secured. The connections between the straps 4 and the webs 3 comprise pivot bolts 5, which pass through the forward end of the webs 3 and through the forward end of the straps 4.

In Fig. 2 in dotted lines, the normal position of the straps before attachment is shown, but, since these straps are flexible, they constitute convenient means for attachment to the two faces of a vertical wall 6 of a store fixture which usually are provided with a finish transverse strip 7, such as is illustrated in Figs. 1 and 2 of the drawing.

Each of the flexible straps 4 is provided with spaced openings 8 for the reception of screws 9, preferably a pair of such attaching screws being provided for each of the straps 4. Since the straps extend backwardly from the facing strip 7 of the store fixture, the fastening screws may be placed in the surface of the vertical walls of the fixture

in such a place that they will be masked by the transverse finish strip 1. Likewise, the straps 4 may be moved longitudinally of the vertical support so that, regardless of the thickness of the finish strip, the straps may be attached to the vertical fixture walls, thereby supporting the replica of the bottle at desired spaced relationship to the front face of the vertical wall section of display fixtures.

The construction, therefore, provides convenient means for the mounting of the display device at desired point-of-sale locations in retail stores and, since the weight of the entire device is small, there will be no substantial strain on the supporting straps.

From the foregoing, it will be understood that the invention accomplishes the objects sought therefor in a convenient, efficient, and economical way.

It should be understood that the invention is not limited to specific details.

What is claimed is:

1. A device of the class described, comprising a replica of a commercial bottle adapted to receive the commercial dress of the container that it simulates, said bottle replica having a cutout portion in one wall thereof, webs oppositely disposed and secured to the interior side wall of said bottle replica, a pair of flexible straps pivoted

to said webs and extending rearwardly through the cutout portion in the body of said bottle, and releasable means for connecting said straps to opposite faces of a vertical support.

2. A device of the class described, comprising a replica of a commercial bottle adapted to receive the commercial dress of the container that it simulates, said bottle replica having a cutout portion in one wall thereof, webs oppositely disposed and secured to the interior side wall of said bottle replica, a pair of flexible straps connected to said webs and extending rearwardly through the cutout portion in the body of said bottle replica, and releasable means for connecting said straps to opposite faces of a vertical support.
